William Shapiro, Toronto, Ontario, Canada, assignor to Electrolite Products Limited, Toronto, Ontario, Canada

Application September 27, 1955, Serial No. 38,127

Term of patent 14 years

(Cl. D85—2)

FIG. 1.

FIG. 2.

Figure 1 is a plan view of a handle for a smoker's stand or similar article embodying my new design, and,

The fragmentary broken line showing of an ash tray in Figure 2 is for illustrative purposes only.

I claim:

The ornamental design for a handle for a smoker's stand or similar article, substantially as shown and described.
